Inventor

UNITED STATES PATENT OFFICE.

RUDOLPH M. HUNTER, OF PHILADELPHIA, PENNSYLVANIA, ASSIGNOR TO
THE GENERAL ELECTRIC COMPANY, OF NEW YORK.

ELECTRIC RAILWAY.

SPECIFICATION forming part of Letters Patent No. 625,168, dated May 16, 1899.

Original application filed May 9, 1887, Serial No. 237,535. Divided and this application filed October 4, 1889. Serial No. 325,957. (No model.)

To all whom it may concern:

Be it known that I, RUDOLPH M. HUNTER, of the city and county of Philadelphia, State of Pennsylvania, have invented an Improvement 5 in Electric Railways, of which the following is a specification.

My invention has reference to electric railways; and it consists of certain improvements, all of which are fully set forth in the following specification and shown in the accompanying drawings, which form a part thereof.

This application (Case No. 113) is a division of my application, Serial No. 237,535, filed May 9, 1887, patented December 24, 1889, No. 15 417,920.

The object of my invention is to provide a railway with two suspended conductors arranged parallel to the track and insulated from each other and supplying electricity 10 to the electrically-propelled vehicle or car through two independently-movable collectors or contact devices, one for each of said conductors, and which collectors may be independently connected to the car, the whole 15 operating so that each may follow any irregularities of its own conductor irrespective of those of the other conductor. This enables the conductors to be placed in operative position without excessive care and greatly 20 cheapens the construction without in the least affecting the working capacity of the system. The collectors may be made in any suitable manner and flexibly connected, so that they 25 may move laterally or vertically with respect to the car or vehicle. My invention also includes suitable switches for crossing suspended conductors, in which the gap necessary may 30 be temporarily bridged for the passage of the collector. These separate collectors supply 35 electricity to the motor on the car, and, if desired, to a secondary battery thereon, which 40 may be employed for supplying current to suitable lighting or heating apparatus on the car or to propel the car over a portion of the 45 track where suspended conductors are impracticable, in which case the collectors would be disconnected. These secondary batteries are preferably located under the seats of the car and inclosed in compartments having

hinged doors on either the outside or inside 50 of the car, or both.

My invention comprehends minor details, which are fully set forth hereinafter.

In the drawings, Figure 1 is a side elevation of an electric railway and car embodying 55 my improvements. Fig. 2 is a sectional elevation of same. Fig. 3 is an elevation showing the arrangement of a crossing track. Fig. 4 is a plan view of same, and Fig. 5 is a cross-section illustrating the modifications of 60 the suspended conductors shown in Fig. 1.

A and B are the two suspended conductors and are supported upon posts C, arranged at intervals apart and connecting with the generator D, which may be provided with a regulator E to control the amount of current passing to line. The conductors A and B may be arranged one above the other, as shown in 65 Figs. 1 and 2, or may be arranged in the same horizontal plane, as shown in Fig. 5, and may 70 be of light wires, rods, or cables.

F is the car and is propelled by an electric motor K, constructed in any suitable manner and mechanically connected with the axle to 75 rotate it. The motor is supported by the axles independently of the car-body and current-collecting devices carried by the latter, so that while the collector supplies current to the motor it is not disturbed by the jarring thereof.

G and H are two independent collectors or contacts adapted to run or move in contact with the conductors B and A, respectively, and are separate and distinct in their movements, each being free to follow irregularities 85 in its own conductor irrespective of the irregularities in the other conductor. These collectors may be made in any suitable manner to produce good contact with little friction. These collectors may be of any suitable 90 construction and are provided with grooved wheels which run along the under side of the conductors. The collector-contacts G and H are connected to conductors I and J, which extend obliquely rearward and respectively connect with the car through detachable socket connections i, whereby they may be readily 95 detached when the car is to continue along

its route and where there are no suspended conductors. These conductors I and J are movably connected with the car, so that their contacts G and H rise and fall or move laterally to follow the suspended conductors. The conductors leading to and connected to the respective collector-wheels are provided on their lower ends with vertical parts which fit into socket-pieces, and hence are adjustable about a vertical axis. The conductors I and J supply current to the motor-circuit P on the car, from which circuit the current may be divided, part passing over the armature-circuit L, provided with a current-reverser I and a resistance-changer M, and another portion passing over the field-magnets N, having a resistance-changer O. By this means the regulation of the motor is easily maintained. In place of the shunt-wound motor any ordinary series-wound motor may be used.

Q are secondary batteries which are located under the seats of the car, being entirely inclosed therein by doors f f' upon the inside and outside of the car, either or both of which doors may be employed. These batteries consist of a number of cells, each connected, preferably, in series, and are charged from the motor-circuit or conductors I and J by a circuit q, provided with a resistance-changer Q' to control the amount of current passing through the battery while being charged.

T is a switch which may be employed to cut the battery out of circuit from the line conductors, or said switch T may be employed to connect the secondary battery in circuit with the electric lamps S in circuit s, resistance-changer Q' being then employed to regulate the current flowing through the lamps. If desired, the secondary battery may also be utilized to supply electric current to the electric heater R, arranged in a circuit R' and provided with a resistance-changer r. This heater may also receive its current direct from the collectors, and its circuit R' may have a circuit-breaker W to cut the heater out of circuit.

p represents an electric-light circuit arranged as a shunt around the motor and is provided with a resistance-changer r to control the amount of current flowing through the lamps. The secondary batteries would not require removal often; but when necessary their removal may be made through the doors f or f'.

In the case of crossing tracks I arrange one track, U, (see Fig. 3,) above the other track, B, and the latter is divided at b, supported by an overhanging arm c from the post C. Pivoted to the end b' is a switch B', which is provided with a weight B² and adapted to span the opening b in the conductor. The divided conductor B has its ends held in position in line by the inverted-V-shaped framework c C and is electrically connected by an electric circuit V to bridge the break in its continuity. As the collector G is moved against the switch

it pushes it down and crosses under the crossing conductor U, and immediately upon passing the switch, through the mediation of its weight or a spring, opens and the passage is free for the collector of the crossing conductor U.

The independently-movable collectors allow the construction of the suspended conductors at a curve to be extremely simple, obviating the necessity of exactness in their relation to each other, and also, if desired, permitting the employment of conductors one above the other. It is also evident that in case the rails were used as a return-conductor in some parts of the line where they could be fairly well insulated or protected the advantage of making the collectors separate would be obvious, as the car could continue on its course with one of the collectors only. In this case we would have a suspended conductor supplying positive current, from which it is delivered to the car by an upwardly-extending collector, and the current after energizing the motor would be delivered to the rails through the wheels of the car. The collectors are to the rear of the sockets i and the connecting-conductors are arranged obliquely and upwardly from the car. The oblique rearward extensions of the conductors of the collectors enable them to follow irregularities and maintain contact with the line conductors A B.

When the electrically-propelled vehicle passes from the portion of the line supplied with the overhead conductors to a portion of the line not supplied with any conductors, then the collector-conductors I J are disconnected at the sockets i, and the secondary battery Q is employed as a source of electric power to operate the motor over such portion of the line as is not supplied with the suspended conductors.

I do not limit myself to the details here shown, as they may be modified in various ways without departing from my invention.

Having now described my invention, what I claim as new, and desire to secure by Letters Patent, is—

1. The combination in a crossing electric railway of a pivoted electric conductor extending along the railway, a pivoted conductor-section adapted to bridge the break in the said pivoted conductor, a transverse conductor arranged across the pivoted conductor upon the distant side thereof and in line with the break, an electric circuit connecting the two sections of the first-mentioned pivoted conductor, and an electrically-propelled car having a current-collecting device adapted to operate the pivoted conductor to automatically cause it to bridge the break in the conductor and acting as a guide for the collector.

2. The combination of two continuous suspended working conductors supplying currents of opposite polarities, arranged at different levels from the ground and in different vertical planes, a series of supporting-poles

common to both conductors, a collector moving in contact with each of said conductors and making an underrunning or moving contact therewith, an electrically-propelled vehicle, 5 and independent upward and rearward connections between said collectors and vehicle.

3. In a crossing electric railway, the combination of two crossing suspended electric conductors insulated from each other one being 10 mechanically divided and the other continuous, and a pivoted or hinged switch in line with said divided conductor and adapted to bridge the break therein during the passage and by the action of the collector device 15 of the car.

4. In a crossing electric railway the combination of two crossing suspended electric conductors one being at a lower level than the other and divided at a point below the 20 other conductor, a conductor bridging the break in the lower conductor, and a pivoted or hinged switch movable on a transverse axis in line with said divided conductor and adapted to bridge the break under the action 25 of the collector device of the car.

5. In a crossing electric railway the combination of two crossing suspended conductors one being at a lower level than the other and divided at a point below the other conductor, a conductor bridging the break in the lower conductor, a pivoted or hinged switch in line with said divided conductor and adapted to bridge the break and means to keep it normally open.

35 6. In an electric railway two crossing electric conductors one of which has an opening in it below the other of said conductors, in combination with a self-opening section to bridge said opening whereby when the collector device is passing over the lower of the conductors the section is closed so that the crossing conductor temporarily secures its continuity, and means to supply electricity of the same potential to the conductor upon 40 each side of the self-opening section.

7. The combination, with one of the crossing electric conductors or power-lines for an electric railway, of a self-opening conducting bridge-piece.

50 8. The combination of a suspended electric conductor having a portion thereof cut away to form a transverse passage-way, framework for rigidly supporting the two ends of the severed conductor in line with each other, and 55 a pivoted bridge-piece loosely pivoted to one end of the divided conductor and adapted during the passage of the collector to span the break in the conductor and allow the free passage of said collector.

60 9. The combination of a suspended electric conductor having a portion thereof cut away

to form a transverse passage-way, framework for rigidly supporting the two ends of the severed conductor in line with each other, and a pivoted bridge-piece loosely pivoted to 65 one end of the divided conductor on a transverse axis with respect to the length of the conductor and adapted during the passage of the collector to span the break in the conductor and allow the free passage of said collector. 70

10. The combination of a divided electric conductor, an inverted-U-shaped framework for supporting the two ends of the conductor in line, a pivoted bridge-piece adapted to bridge the break and allow the free passage 75 of the collector, and a transverse continuous conductor passing through the inverted-U-shaped frame above or at a higher elevation than the break in the first-mentioned conductor. 80

11. The combination, with crossing electric conductors for an electric railway, of one or more conducting bridge-pieces suitably hung or supported to swing in a vertical plane and adapted to bridge the gap left in the path of 85 the trolley or contact for one of said conductors at the point where the trolley or contact of the crossing conductor passes.

12. In an electric railway, a vertically swinging contact-bridge B', operated by the 90 trolley and normally standing in position to permit the contact or trolley of a crossing conductor to pass without obstruction.

13. The combination of a conductor A, adapted to be engaged by a traveling contact, 95 a second conductor B, crossing over the first, and a swinging contact-bridge pivoted to swing in a vertical plane in the space below the conductor A and electrically connected with the line or conductor B. 100

14. The combination, with electric conductor B, parts of which, at opposite sides of conductor A, are electrically united, of the conducting bridge-piece adapted to bridge the space beneath the conductor A. 105

15. The combination, with an electric conductor engaged by a traveling contact device and having its continuity normally interrupted, of a second conductor continued over the first so as to be mechanically and electrically continuous, and a movable bridge-piece for the former adapted to normally rest to one side of a vertical plane through the second conductor and to swing or move beneath the said conductor under the action of 115 the traveling contact.

In testimony of which invention I have hereunto set my hand.
